CLAIM

The ornamental design for an air purifier, as shown and described.

DESCRIPTION

FIG. 1 is a front, right-side, and top view of an air purifier showing the new design.

FIG. 2 is a front elevation view of the air purifier.

FIG. 3 is a back elevation view of the air purifier.

FIG. 4 is a left-side elevation view of the air purifier.

FIG. 5 is a right-side elevation view of the air purifier.

FIG. 6 is a bottom plan view of the air purifier; and,

FIG. 7 is a top plan view of the air purifier.

The broken lines depict elements of the air purifier that form no part of the claimed design.

1 Claim, 5 Drawing Sheets(56)
